UNITED STATES PATENT OFFICE

RUDOLPH L. HANAU, OF BUFFALO, NEW YORK, ASSIGNOR TO HANAU ENGINEERING COMPANY, INC., OF BUFFALO, NEW YORK, A CORPORATION OF NEW YORK

DENTAL BLOWTORCH

Application filed December 13, 1927. Serial No. 239,679.

My invention relates to improvements in dental blow torches.

The primary object of my invention is the production of a simple, inexpensive, and compact device of this kind, wherein provision is made to secure a sustained or an intermittently projected flame to be used for various dental operations, and wherein means is embodied to regulate the size of the projected flame so that it may be used to maximum advantage under the various steps employed in the production or modeling of dental impressions, and other dental objects.

A further object of my invention is the production of a device of this kind, which is easily manipulated, compact in size and therefore always ready for use, and one which is adapted for various kinds of dental operations.

20 A still further object of my invention is to provide a torch of the kind described with a pressure-inducing device, an air nozzle, and an air-storage chamber between the pressure-inducing device and the air nozzle in which air under pressure is maintained so that a continuous or sustained flame will be projected from the device without the need of continuously operating the pressure-inducing device.

30 With the above and other objects in view, the invention consists in the novel features of construction, and in the combination and arrangement of parts to be hereinafter described and more particularly pointed out in

35 the subjoined claims.

Referring to the drawings:

Fig. 1 is a central vertical section of the device.

Fig. 2 is a cross section taken on line 2—2, 40 Fig. 1.

Fig. 3 is a cross section taken on line 3—3, Fig. 1.

Fig. 4 is a vertical section taken through the upper part of the torch on the plane indicated by line 4—4, Fig. 2.

Fig. 5 is a cross section taken on line 5—5, Fig. 1.

Fig. 6 is a perspective view of part of the device serving to restrict the air in its passage upwardly to the nozzle.

Fig. 7 is a cross section taken on line 7—7, Fig. 1.

Fig. 8 is a detached perspective view of the air-relief valve.

The device may be constructed of any desired material and under any desired method, and it has a body 10 enlarged at its upper and lower ends to form a head 11 and base 12, respectively, the lower end being preferably of greater diameter than the upper. The head 60 11 and the part 13 between said head and the base may, for convenience be termed the upper portion of said body, while the base may be considered the lower portion. The base 12 is made hollow and the upper portion of 65 the body has a vertical bore 14 formed therethrough, which extends downwardly from the upper end of the body to the interior of the base 12; the upper end of this bore being somewhat enlarged and internally screw-threaded to receive the lower reduced screw-threaded end 15 of a gland 16. This gland has its upper end enlarged and internally screw-threaded to receive an adjustable sleeve 17. 70

A wick tube 18 is passed through the gland and tightly fitted into the lower reduced portion thereof, while the adjustable sleeve 17 is loosely arranged around the wick tube 18 so that it may be adjusted to bring the upper end 75 thereof any desired distance above the upper end of the wick tube 18, for a purpose to appear hereinafter.

The exterior of the enlarged upper end of the gland 16 is knurled or otherwise roughened so that it can be easily grasped and threaded into the upper end of the body 10, and the exterior of the adjustable sleeve 17 is also knurled or otherwise roughened above its screw-threaded portion so that it may be 80 easily adjusted within the gland, said upper knurled or otherwise roughened portion of the adjusting sleeve extending upwardly a distance above the upper end of the gland 16. The upper portion of the body is also hollow 85 to form a crescent-shaped compressed-air storage-chamber 19 therein which, in the form the body is cast, opens at its lower end into the hollow base and which has its upper end reduced in size, as at 20. 90

The lower end of the base is closed by means of a closure plate 21, which is forced against a gasket 22 firmly seated against a shoulder 23 formed in the base 12, this closure plate being 5 therefore liquid-tight. The lower end of the crescent-shaped air chamber 19 is also closed by a plate 24 in air-tight manner. The hollow base is therefore converted into a liquid fuel chamber, which I designate by the 10 numeral 25, and into which a wick 26 extends; this wick being passed downwardly through the wick tube 18 and through the bore 14 formed in the body 10. The upper end of this wick extends the desired distance above 15 the wick tube to provide a flame which is to be projected under intermittent or sustained air currents, in a manner to be described hereinafter.

Fitted onto the body 10, between the base 20 12 and the head 11, is a compressible rubber bulb 27, the bulb being substantially spherical and having openings 28, 29 at its upper and lower ends. The body portion is provided with an outstanding flange 30 a distance beneath the head 11 to provide an annular groove or seat 31 on the body 10 directly beneath the head, and it also has a second outstanding flange 32 a distance above the hollow base 12 to form an annular groove or 25 seat 33 directly above said base. The rubber bulb, being elastic, is passed downwardly over the head 11 onto the portion of the body between said head and the base so that the upper and lower portions of the bulb, or more particularly the walls of the openings 28 and 30 in said bulb, are seated against the annular seats 31 and 33 provided on the body 10, the bulb thus having an air-tight fit on said body.

Formed in the body and extending downwardly from the upper end thereof is a pocket 34, the lower portion of which is reduced in diameter to form a valve chamber 35, and the upper portion of which is screw-threaded 40 to receive an externally-threaded air-restricting sleeve 36 which extends upwardly beyond the body 10. The enlarged upper portion of this pocket is in communication with the reduced upper end 45 of the air chamber 19 through the medium of a port 37. An angular air passage 38 connects the interior of the bulb 27 with the valve chamber 35. The air passage 38 opens laterally into said bulb and upwardly axially into said valve 50 chamber to form a valve seat 39 and it is closed by a gravity or ball valve 40 which has limited movement vertically within said valve chamber, as will appear hereinafter.

By reducing the diameter of the lower end 55 of the pocket 34, an upwardly-facing shoulder 41 is provided in said pocket. The lower end of the air-restricting sleeve 36 is spaced from said shoulder, as at 42, to form a primary air chamber, which is in communication 60 with the compressed-air storage-chamber 19

through the medium of the port 37. Fitted into the lower end of said sleeve 36 is a plug 43, which has a longitudinal groove 44 in its peripheral face and an axial depending stoppin 45 which extends into the valve chamber 70 35. The interior of the sleeve 36 is in connection with the primary air chamber 42 through the medium of the groove 44, which may be referred to as an air-restricting passage, and therefore this primary air chamber 75 is in connection with the interior of said sleeve, as well as with the interior of the compressed-air storage-chamber 19, and it is to be noted that the port 37 between this primary air chamber is considerably larger than 80 the air restricting passage 44. It is, of course, understood that in lieu of the plug 43 serving to close the lower end of the sleeve 36, this sleeve may be otherwise closed at this point, and the restricting air passage provided between the interior thereof and the primary air chamber 42 be formed in any other approved manner.

In the top of the body 10 around the projecting portion of the externally-threaded sleeve 36, a depression 46 is formed, in which a gasket 47 is disposed, and onto the projecting portion of said sleeve a nozzle holder or carrier 48 is threaded, the lower end of which is in firm contact with said gasket 47 to assure an air-tight joint at this point. The bore 49 through this nozzle holder or carrier is restricted at its upper end, and threaded into the restricted portion of said bore from the side of said nozzle holder or carrier, is a 100 nozzle 50 having a comparatively small exit opening 51. The restricted portion of the bore 49 extends to the upper end of said nozzle holder and the upper portion thereof is threaded to receive the threaded shank 52 of 105 a pressure-relief screw 53 which has an enlarged knurled head, between which and the upper end of said nozzle holder or carrier, a gasket 54 is arranged. The threaded shank 52 of this pressure-relief screw is cut away 110 at one side along its full length, as at 55, forming an air-relief pressure or by-pass 56 along said shank, which, however, is closed in an air-tight manner by the gasket 54 when the screw is tightened into the upper reduced end 115 of the bore in said nozzle holder or carrier. This air-tight condition is established, due to the fact that the head of said pressure-relief screw bears tightly against said gasket. When slightly unthreading said pressure-relief screw, the relief passage or by-pass 56 will be opened to the outer air so as to allow the escape of a quantity of air passing upwardly through the nozzle holder or carrier, as will be hereinafter described. The nozzle 120 50 is disposed to direct a current of air across the lighted end of the wick 26.

For convenience in manufacturing, a transverse bore 57 is formed through the nozzle holder or carrier so as to intersect the reduced 125

upper end of the bore 49 extending longitudinally therethrough, and this transverse bore is threaded at one side of the reduced upper end of said bore to receive the reduced inner end 58 of the nozzle 50, while that portion of the transverse bore at the opposite side of said reduced upper end is closed by a screw plug 59.

One or more air-inlet passages 60 are provided in the body 10, each of which includes 10 a vertical branch 61 extending downwardly from the upper end of the body 10, a horizontal branch 62 extending from the lower end of said vertical branch to the interior of the compressible bulb 27, and a horizontal 15 branch 63 extending from said vertical branch a distance from its upper end outwardly to the exterior air, this arrangement being provided for convenience in manufacture. The upper end of the vertical branch 20 of each air-inlet passage 60 is slightly enlarged and screw-threaded to receive a screw plug 64; thus each air-inlet passage has an air inlet at one end and an air-outlet at its other end, and is otherwise closed.

25 The horizontal branch 63 of each air-inlet passage is reduced in diameter at its inner end, as at 65, to form the inner end wall of a valve-chamber 66, and it is enlarged at its outer end to form an outwardly-facing shoulder 67. In the enlarged outer end of each horizontal branch 62 a short brass or other sleeve 68 is fitted, the inner end thereof bearing against the shoulder 67 and forming a 30 valve seat. That portion of each horizontal branch 62 between its sleeve 68 and the reduced inner end 65 thereof serves as the valve chamber 66, referred to, and arranged therein is a ball valve 69 adapted to close against the valve seat at the inner end of the sleeve 68. 35 It is to be understood that this ball valve does not at any time close the reduced inner end 65 of the branch 63 in an air-tight manner. These air-tight passages 60 lie at opposite sides of a plane passing vertically through 40 the wick tube and the air-restricting tube 36. The device is ordinarily used by slightly 45 tilting it so that the nozzle is inclined downwardly, which results in the ball valves 69, arranged in the air-inlet passages 60, rolling 50 against their valve seats at the inner ends of the sleeves 68.

It may, for certain purposes, be found desirable to have the horizontal branches 63 open into the vertical branches 61 of the air-inlet passages from the opposite side of the body 10, and for this purpose, when die-casting this body, all of these horizontal branches are only partly formed in the body, as indicated at the right in Figs. 2 and 3. Thus formed, and designated by the numeral 63^a, they are directed toward the vertical branches from opposite sides of the body, but are not in communication therewith. The reduced portions 65 of the horizontal branches 62 of

the air-inlet passages are therefore provided by machining a connection between the selected partly-formed branches 63^a and the vertical branches 61; thus forming the completed horizontal branches 63 shown at the left in Figs. 2 and 3. Therefore, one or both of the partly-formed branches 63^a at either side of the vertical passages 61 may be completed and the ball valves and their seats inserted into them. When the device is mainly 70 used in a position in which the nozzle is inclined downwardly during use, the branches 63 will be at the left, as shown in Figs. 2 and 3; whereas, when the device is used in directing the flame upwardly, due to the air 75 nozzle being so disposed, the branches at the right in Figs. 2 and 3 will be utilized. In either case, the tendency is for the ball valves to roll against their seats, and thus close said air-inlet passages.

Broadly considered, the air passage 38, the valve chamber 35, the primary air chamber 34, the sleeve 36 with its restricted passage 44, and the nozzle holder or carrier 48 with its nozzle, serve as an air-outlet passage which 80 extends from the bulb to the exit opening 51 of the nozzle; and in the claims, unless parts of this air-outlet passage are specifically set out, all of said parts, or parts serving the same purpose, are to be construed as such 85 unit.

The liquid fuel within the chamber 25 is drawn upwardly to the upper end of the wick 26 by capillary attraction, and after lighting the upper end of this wick, the flame therefrom may be regulated by the adjusting sleeve 17, the upper end of which is moved outwardly over the free end of the wick tube 18 to the desired extent. Upon compressing the bulb 27, the air therein and in the lower portion 100 of the air outlet passage is compressed, the ball valve 40 in said passage becomes unseated and part of the compressed-air passes into the air storage-chamber and a smaller part through the air restricting passage 44 in the sleeve 36. The expansion or recovering movement of the bulb draws the ball valve 40 to its seat and prevents the return of compressed-air from the air storage-chamber 105 110 back into the bulb; at the same time, the ball valves in the air inlet passages 60 become unseated from the ends of the sleeves 68, thus providing a continuous passage for admission of atmospheric air to the interior of the bulb. Further compression of the bulb results in the 115 air drawn thereinto being forced out through the lower portion of the air outlet passage, part thereof entering the compressed-air storage-chamber 19 and a smaller part passing out through the restricted air passage 44.

This action is continued until sufficient pressure is created within the compressed-air storage-chamber, after which slight intermittent pressure on the bulb with intervening expanding or recovering movements will pro- 120 125 130

vide all the air that can possibly escape through the air-restricting passage 44, the air through said passage being provided both from the bulb and the compressed-air storage-chamber and escaping out through the nozzle, 5 where it is directed against the flame and causes the flame to be directed laterally from the end of the wick. The successive compressions and expansion movements of the bulb results in a considerable amount of air 10 being stored in the compressed-air storage-chamber 19, and therefore a continuous flow of air is provided from the nozzle so that a constant or sustained flame may be directed laterally from the wick. When, however, an 15 intermittently projected flame is desired, the relief screw 53 at the top of the device is slightly unthreaded so as to unseat the head thereof from the upper end of the nozzle holder or carrier, thus uncovering the relief 20 air passage 56 at the flat side of said relief screw and allowing a portion of the air directed to the nozzle to escape through said relief passage.

25 When the relief passage 56 is opened, it will be necessary to continuously cause compression and expansion movements of the pressure-inducing bulb 27.

By means of this device the flame projected 30 from the upper end of the wick tube may be governed to a nicety and the temperature applied to the dental impression or other article being worked upon, controlled according to need.

35 Having thus described my invention, what I claim is:—

1. A dental blow torch, comprising a body having a fuel supply and a wick extending from said fuel supply and projecting outwardly therefrom, said body having an air storage chamber therein, a nozzle carried by said body and disposed at an angle to the projecting end of said wick, and an air pressure-inducing device carried by said body and having an air inlet and an air outlet, said air outlet having communication with said air storage chamber and said nozzle.

2. A dental blow torch, comprising a body having a liquid fuel chamber at its lower end, 50 a wick bore extending from the upper end of said body to said liquid fuel chamber and a compressed-air storage-chamber adjacent said wick bore, a wick extending through said wick bore and entered into said liquid fuel chamber, said wick projecting from said bore at the upper end of said body, a compressible bulb surrounding said body, said body, having a valve-controlled air inlet passage leading to the interior of said bulb and a valve-controlled air outlet passage extending through said body and opening into said bulb, 55 said valve-controlled outlet passage having communication with said compressed-air storage chamber, and an air nozzle at the upper end of said body and disposed at an angle

to the projecting end of said tube, said nozzle being in communication with said air outlet passage and with said compressed-air storage-chamber.

3. A dental blow torch, comprising a body reduced in diameter between its upper and lower ends and having a liquid fuel chamber at its lower end and a compressed-air storage-chamber above said liquid fuel chamber, a compressible bulb surrounding the reduced portion of said body, a wick extending from said liquid fuel chamber upwardly through said body and projecting from the upper end thereof, a valve-controlled air inlet passage leading to the interior of said bulb, an air nozzle mounted on said body at right angles to said wick so as to discharge a current of air across the projecting end of said wick, and a valve-controlled air outlet passage leading from the interior of said bulb to said nozzle, said valve-controlled air outlet passage having communication with said compressed-air storage-chamber between said nozzle and the controlling valve in said air outlet passage.

4. A dental blow torch, comprising a body reduced in diameter between its ends to form a head at its upper end and a base at its lower end, said body having annular flanges on its reduced portion spaced, respectively, from said head and said base to form grooves, a compressible bulb surrounding said reduced portion and being fitted into said grooves, said base being hollow and serving as a liquid fuel chamber and the remainder of said body being hollow and divided longitudinally to serve as a compressed-air storage-chamber and a wick bore, a wick in said bore extending into said liquid fuel chamber and projecting from the upper end of said bore, an air nozzle mounted on said body and disposed to direct a current of air across the upper projecting end thereof, means to control the admission of air to said bulb, and means to control the discharge of air from said bulb under pressure, said last-mentioned means leading to said air nozzle and to said compressed-air storage-tank.

5. A dental blow torch, comprising a hollow body having a liquid fuel chamber and a compressed-air storage-chamber, a compressible bulb surrounding said body, a wick leading from said liquid fuel chamber and extending upwardly through said body to project from the upper end thereof, an air nozzle mounted on said body and disposed to cause a current of air to intersect the flame at the projecting end of said wick, an air inlet passage for said bulb, an air outlet passage leading from said bulb to said nozzle, said air outlet passage having connection at a point between its ends with said compressed-air storage-chamber, and air-restricting means in said air outlet passage disposed between

- the connection thereof with said air storage chamber and said nozzle.
6. A dental blow torch, comprising a hollow body having a liquid fuel chamber at its lower end and a compressed-air storage-chamber above said liquid fuel chamber, a wick leading from said liquid fuel chamber and extending upwardly along said compressed-air storage-chamber and being separated therefrom by a wall, said wick projecting from the upper end of said hollow body, an air nozzle mounted on said body and disposed to cause a current of air to intersect the flame at the projecting end of said wick, a compressible bulb surrounding said body, an air inlet passage for said bulb, and an air outlet passage leading from said bulb to said nozzle and having means to restrict the current of air passing to said nozzle, said air outlet passage having also unrestricted connection with said compressed-air storage-chamber.
7. A dental blow torch, comprising a hollow body having a liquid fuel chamber at its lower end and a compressed-air storage-chamber above said liquid fuel chamber, a wick leading from said liquid fuel chamber and extending upwardly along said compressed-air storage-chamber and being separated therefrom by a wall, said wick projecting from the upper end of said hollow body, an air nozzle mounted on said body and disposed to cause a current of air to intersect the flame at the projecting end of said wick, a compressible bulb surrounding said body, an air inlet passage for said bulb, and an air outlet passage leading from said bulb to said nozzle and having means to regulate the current of air passing to the exit-opening of said nozzle so as to issue an intermittent or a constant current of air therefrom against said flame, said air outlet passage having also unrestricted connection with said compressed-air storage-chamber.
8. A dental blow torch, comprising a hollow body having a liquid fuel chamber at its lower end and a compressed-air storage-chamber above said liquid fuel chamber, a wick leading from said liquid fuel chamber and extending upwardly along said compressed air storage chamber and being separated therefrom by a wall, said wick projecting from the upper end of said hollow body, an air nozzle mounted on said body and disposed to cause a current of air to intersect the flame at the projecting end of said wick, a compressible bulb surrounding said body, an air inlet passage for said bulb, an air outlet passage leading from said bulb to said nozzle and having means to restrict the current of air passing to said nozzle, said air outlet passage having also unrestricted connection with said compressed-air storage-chamber, and a controlled air relief passage in said air outlet passage whereby an intermittent or

a constant current of air is caused to escape from said air nozzle and pass over the projecting end of said wick.

9. A dental blow torch, comprising a hollow body, air pressure-inducing means supported by said body and having a valve-controlled air outlet passage, a wick within said body and projecting therefrom, a nozzle directed toward the projecting end of said wick to direct air currents across the same and to which said air outlet passage leads, and means in said air outlet passage for controlling the passage of air through said nozzle so as to cause intermittent currents or a constant current of air to issue therefrom. 75

10. A dental blow torch, comprising a body having a wick projecting therefrom and means to feed said wick by capillary attraction with a liquid fuel, a nozzle carrier mounted on said body having an air nozzle disposed in a plane above the projecting end of said wick so as to direct currents of air over said wick, an air pressure-inducing device carried by said body, a valve-controlled air inlet passage in said body leading to said air pressure-inducing device, a valve-controlled air outlet passage in said body leading from said air pressure-inducing device to said nozzle carrier, and means between said air outlet passage and said air nozzle whereby all air entering said nozzle carrier may be directed outwardly through said nozzle or a portion of said air be allowed to escape from said nozzle carrier, the air escaping from said nozzle being directed across the 100 projecting end of said wick. 95:

11. In a dental blow torch, a body having air pressure-inducing means and a wick projecting therefrom, an air escape nozzle adapted to direct a current of air across the projecting end of said wick, an air passage leading from said air pressure-inducing means to said nozzle, an opening in said air passage, and a pressure relief device fitted within said opening and adapted to close the 110 same or open the same to any desired extent within said certain limits.

12. In a dental blow torch, a body having air pressure-inducing means and a wick projecting therefrom, an air escape nozzle 115 adapted to direct a current of air across the projecting end of said wick, an air passage leading from said air pressure-inducing means to said nozzle, a screw-threaded opening in said air passage adjacent said nozzle, and an air relief screw having a head and being cut-away at one side to form an air passage when the screw is partly unthreaded. 120

13. A dental blow torch, comprising a hollow body having a wick projecting therefrom, an air pressure-inducing device carried thereby, an air escape nozzle disposed to direct a current of air across the projecting end of said wick, a valve-controlled air outlet passage in said body leading from said 130

air pressure-inducing device to said nozzle and an air inlet passage in said body leading from the exterior thereof to the interior of said air pressure-inducing device, said air inlet passage being reduced in diameter at a point along its length to form a shoulder, a sleeve fitted into said air passage in spaced relation to said shoulder, and a ball valve within the space between said sleeve and shoulder and adapted to close against said sleeve to prevent the admission of air into said passage, said shoulder being formed to prevent the complete closure of said ball valve thereagainst.

14. A dental blow torch, comprising a body having a wick projecting therefrom, a compressible bulb surrounding said body and secured thereto in an air-tight manner, a valve-controlled air inlet for said bulb, a sleeve threaded into said body and having a restricted air passage at its lower end, an air outlet passage leading from said sleeve to the interior of said bulb, a valve within said air outlet passage adapted to prevent the admission of air into said bulb but permit the passage of air therefrom, a nozzle carrier threaded onto said sleeve, and a nozzle projecting laterally from said nozzle carrier and disposed to direct a current of air across the projecting end of said wick.

15. A dental blow torch, comprising a hollow body having a liquid fuel chamber and a wick extending from said liquid fuel chamber outwardly to project from the upper end of said body, a compressible bulb surrounding said hollow body and secured thereto in an air-tight manner, a sleeve threaded into said hollow body from the upper end and projecting outwardly therefrom, a plug fitted into the lower end of said sleeve and having a longitudinal groove therein to form an air-restricting passage, said plug having a depending stop pin axially thereon, an air passage leading from said sleeve to the interior of said bulb and having a reduced portion serving to form a valve seat, a valve in said passage between its seat and the end of said depending stop pin, a nozzle carrier threaded onto the projecting end of said sleeve, and a nozzle extending laterally from said nozzle carrier and disposed to direct a current of air across the projecting end of said wick.

16. A dental blow torch, comprising a body having air pressure-inducing means and a nozzle connected with said air pressure-inducing means, said body having a liquid fuel chamber at its lower end and a wick bore extending from said liquid fuel chamber to the upper end of said body, a gland fitted into the upper end of said bore, a wick tube fitted into said gland and extending upwardly a distance above the same, an adjustable sleeve surrounding said wick tube and capable of being adjusted to have its upper end project above the upper end of said wick

tube to any desired degree, and a wick fitted into said wick tube and extending into said liquid fuel chamber, said wick extending above the upper end of said wick tube and adapted to have the flame thereof, when lighted, receive a current of air from said nozzle.

17. A dental blow torch, comprising a hollow body having a liquid fuel chamber at its lower end and a wick bore extending upwardly from said liquid fuel chamber and opening at the upper end of said body, said bore having its upper end enlarged and screw threaded, an air escape nozzle at the upper end of said body, air pressure-inducing means connected with said nozzle, a gland screw-threaded into the screw-threaded upper end of said wick bore and having its upper end internally screw threaded and its lower end provided with a smooth bore, a wick tube fitting into said smooth bore and extending upwardly beyond the upper end of said gland, an adjustable sleeve surrounding said wick tube and screw-threaded into the upper end of said gland, said adjustable sleeve being capable of adjustment to bring the upper end thereof above the upper end of said wick tube, and a wick fitted into said wick tube and extending downwardly therefrom into said liquid fuel chamber, said wick projecting from the upper end of said wick tube and said nozzle being disposed to direct a current of air across the projecting end of said wick.

18. A dental blow torch, comprising a body supporting all parts of the torch and having a fuel supply therein, a wick therein extending from the upper end thereof and receiving fuel from said supply, an air nozzle supported by said body in operative relation to said wick, a pressure-inducing device surrounding said body, and means interposed between said pressure-inducing device and said air nozzle in conduit connection with both to assure a constant current of air from said air nozzle over a comparatively long period of time.

19. A dental blow torch, comprising a fuel supply, a wick receiving fuel from said supply, an air nozzle in operative relation to said wick, a pressure-inducing device, and means between said pressure-inducing device and said air nozzle in connection with both whereby intermittent currents of air, or a constant current of air, is caused to be directed from said air nozzle over the end of said wick.

In testimony whereof I affix my signature.
RUDOLPH L. HANAU.
